(57) **CLAIM**

The ornamental design for a white noise wake up clock, as shown and described.

DESCRIPTION

FIG. 1 is a perspective view of a white noise wake up clock design showing my new design.

FIG. 2 is a front view of the white noise wake up clock.

FIG. 3 is a rear view of the white noise wake up clock.

FIG. 4 is a left side view of the white noise wake up clock.

FIG. 5 is a right side view of the white noise wake up clock.

FIG. 6 is a top view of the white noise wake up clock; and,

FIG. 7 is a bottom view of the white noise wake up clock.

The shading lines shown in the drawings are utilized to illustrate the surface contours of the white noise wake up clock design in the drawings, and form no part of the design. The broken lines shown in the drawings illustrate portions of the article that form no part of the claimed design.
